J. REIFFENSTEIN.

STOVE OR RANGE.

No. 17,121.

Patented Feb. 15, 1887.

UNITED STATES PATENT OFFICE.

JOHN REIFFENSTEIN, OF SYRACUSE, NEW YORK, ASSIGNOR TO THE SYRACUSE STOVE COMPANY, OF SAME PLACE.

DESIGN FOR A STOVE OR RANGE.

SPECIFICATION forming part of Design No. 17,121, dated February 15, 1887.

Application filed December 24, 1886. Serial No. 229,513. Term of patent 7 years.

To all whom it may concern:

Be it known that I, JOHN REIFFENSTEIN, a citizen of the United States, residing at Syracuse, in the county of Onondaga and State of New York, have invented and produced a new and original Design for Stoves and Ranges; and I do declare the following to be a full, clear, and exact description of the same, reference being had to the accompanying engraving, forming a part thereof, which is a perspective view of a range embodying my design in configuration and ornamentation.

A represents the base upon which the range is mounted, and which is supported, in the usual manner, by the legs a. This base is ornamented by a band, b, on each face and extending lengthwise, arranged in the form of successive rectangular loops c c, turned upward, except the center one, d, which is a double loop turned downward beyond the line of the lower edge of the face. The ends are turned inward in the form of a rectangular scroll, e. Within the central loop, d, is a flower, f, having its leaves 2 2 flaring from opposite sides of the flower. A flower or plant, 3, with flaring leaves also projects inwardly toward the center from each end scroll, and garlands 4 are suspended from the loops on each side of the central one.

30 The corners B are embellished by an embossed face surrounded by a plain raised band, 5.

The legs a are ornamented by a plain raised band, f, around the margin, inclosing a garland, g, within the upper and central portion.

The larger or oven doors are ornamented by a raised panel encompassed by horizontal parallel raised lines i i near top and bottom and intersecting vertical parallel raised lines k k at the sides. Within these parallel lines are flowers 6, and without and around the outer margin are rosettes 7. Within the central rectangular space, and inclosed by the lines, are flowers, over which appear the words "The New Superb" in raised letters, the words "The New" being smaller, arranged vertically, and surrounded by an ornamental circular scroll.

The ornamentation of the smaller doors is similar to that of the larger, except that the parallel lines and the row of flowers between are omitted, and only single raised horizontal

and vertical lines at top and bottom and sides appear. Within the central rectangular space inclosed by the lines is a large letter "S," embracing within its top curve a smaller letter "S" and within the bottom curve the letters "C. O."

The front or fire door, H, is ornamented by a row of octagonal depressed panels across its upper portion and covering nearly the entire upper half of the door. Across the center is a horizontal depression, each end of which is embellished by a row of circular or wheel-shaped figures having stems inclining inwardly toward the damper below, the central portion of the slot or depression being open. Beneath this is the damper, the sides of the openings to which are ornamented by net-work or oblique crosses. Above this door is a draft-door, I, extending across the front, and ornamented by a row of octagonal-shaped depressed panels.

Upon the top of the range proper is mounted a warming-closet, C, supported upon brackets D, of open lattice-work, and on the back wall of the support, on one side, between the bracket 75 and smoke-flue, is an embossed figure of a dancing Greek slave or female figure, E, and on the opposite side a dancing male figure, F. The interior ground of the rear wall is also ornamented with a pictorial illustration of the 80 interior of a palace.

The ornamentation of the doors of the warming-closet is similar to that upon the smaller doors before described, except that the rectangular space within the raised lines in one 85 incloses the word "Warming" and in the other "Closet."

Upon the face of the smoke-flue, beneath the warming-closet, is a large letter "S," inclosing within its curves the smaller letters "S" and "C. O.," as before described, on the face of the smaller doors. Surrounding this are parallel raised lines, and both above and beneath the letter "S," and within the raised lines, are rows of oblique crosses. Beneath this ornamentation is the flue-damper, on each side of the openings of which is a leafed stem bearing a single flower.

The end panels of the warming closet consist of a checkered internal field surrounded by a raised molding, m, inclosing which is a row of rosettes, n, and around the whole, and forming

J. R.

the outer border of the panel, is a plain raised band, o.

Having thus described my invention, what I claim, and desire to secure by Letters Patent, 5 is—

1. In a design for stove or range, the ornamental base having a band arranged in successive loops and extending lengthwise across its face, with a flower in the center of the central loop with leaves turned outward, and garlands suspended from the looped band, substantially as shown and described.

2. In a design for stove or range, the leg thereof, having a plain raised band around the margin inclosing a garland within the upper and central portion, substantially as shown and described.

3. In a stove or range, the design for the doors thereof, consisting of the raised panel encompassed by raised lines or bars having flowers between the raised lines, ornamental letters or figures within the central rectangular space, and rosettes around the margin, substantially as shown and described.

25 4. In a design for stove or range, the front door, II, ornamented with a row of octagonal depressed panels in its upper portion, a central horizontal depression, a row of wheel-shaped figures at each end of such depression, and damper-openings below ornamented at 30 their sides with net-work or oblique crosses, substantially as shown and described.

35 5. In a design for a stove or range, the configuration of the high warming-closet supported upon the open lattice-work brackets,

and having embossed upon the rear wall of the support a female dancing figure on one side of the smoke-flue and a male figure on the opposite side, substantially as shown and described.

6. The design in stoves and ranges, consisting of the panel on the face of the smoke-flue of the high warming-closet, having a monogram in its center inclosed within embossed parallel lines or bars, between which, above and beneath the monogram, are rows of oblique 45 crosses, substantially as shown and described.

7. In a design for stove or range, the configuration of the open lattice-work brackets supporting the warming-closet, substantially as shown and described.

50 8. The design in stoves and ranges, consisting of the rear wall of the support of the high warming-closet, ornamented by the pictorial illustration of the interior of a palace, showing Byzantine pillar and balustrade, mosaic 55 floor, and frescoed wall, substantially as shown and described.

9. In a design for stove or range, the end panels of the warming-closet and vertical sides of the range, consisting of the checkered field 50 inclosed by the raised molding and surrounding same a single row of rosettes, substantially as shown and described.

In testimony whereof I affix my signature in presence of two witnesses.

JOHN REIFFENSTEIN.
